UNITED STATES PATENT OFFICE.

MAURICE D. VAN LENTEN, OF PATERSON, NEW JERSEY.

APPARATUS FOR DELIVERING ARTICLES, SUCH AS MAIL-BAGS, FROM TRAINS OR MOVING BODIES.

1,074,027.

Specification of Letters Patent. Patented Sept. 23, 1913.

Application filed March 1, 1913. Serial No. 751,638.

To all whom it may concern:

Be it known that I, MAURICE D. VAN LENTEN, a citizen of the United States, residing at Paterson, in the county of Passaic and State of New Jersey, have invented certain new and useful Improvements in Apparatus for Delivering Articles, such as Mail-Bags, from Trains or Moving Bodies, of which the following is a specification.

10 My invention relates to an apparatus for delivering articles such as mail-bags from trains or moving bodies.

One object of the invention is to provide in a device of this kind a turnable receiving or catching arm that will move or actuate in such manner subsequent to the reception or catching of a bag thereby, as not to impart severe shocks or jolts to the several parts of the apparatus.

20 A second object is to provide latch means for maintaining the arm in projected position preparatory to a catch, operable to release the arm upon the catching of a bag.

A third object is to provide means whereby the arm will be positively turned or moved upon the actuation of the latch means.

A fourth object is to provide means to operate in connection with the arm so as to exert braking action thereon or a part thereof to regulate the speed at which the arm turns and its extent of turning movement.

A fifth object is to provide the apparatus of such construction that a lock arm for the catch hook employed, may serve as a means to be engaged by the bag or other article to actuate the latch means mentioned.

A sixth object is to provide an improved construction of means for holding or supporting a bag or article as from a car, in position to be caught.

Further objects are to provide a device that employs parts few in number, simple in construction, durable in operation, and hence a device that will prove efficient and may be manufactured at minimum cost.

The preferred embodiment of the invention is described hereinafter and illustrated in drawings accompanying this application.

50 In said drawings:—Figure 1 is an elevation illustrating the apparatus in connection with a car, the end thereof being partly

shown and a mail-bag projected therefrom in position to be caught; Fig. 2 is an enlarged vertical sectional view through the 55 turnable head for the arm illustrating therein in elevation, the means for securing the arm in projected position, and the means for braking the turnable head during its movement; Fig. 3 is a cross sectional view on the line 3—3 of Fig. 2; Fig. 4 is a vertical sectional view illustrating the catching arm and turnable head thereon, together with the means carried thereby; Fig. 5 is an elevation looking toward the outer end of the 65 catching arm illustrating parts of the catch mechanism; Fig. 6 is an elevation illustrating a part of the bracket for supporting the ring attached to mail-bags and the like, said ring being shown fastened to the support; 70 and Fig. 7 is a perspective view illustrating said bracket ring and supporting means.

The article illustrated as being transferable from a car, is shown as a mail-bag which is fastened to a member to which may 75 be fastened a plurality of the bags so that the same may be transferred as a unit.

Throughout the several views of the drawings, like reference characters designate like or similar parts.

Referring specifically to the drawings, 1 designates a car or moving body from one side of which may be projected a bracket or arm 2. This bracket 2 is mounted to swing relatively to the side of the car and is capable of movement vertically on a rod 3 of a suitable bracket fastened to the car. To the arm 2 is fastened a support rod 4 which is adapted to enter a socket in a bracket 5 when the arm 2 is in projected position, so 90 that the arm will be readily supported in such position. In swinging the arm 2 toward the car or interiorly thereof when not in use, said arm is first raised so that the lower portion of rod 4 will disengage its 95 socket in order to permit the swinging movement.

Near the outer end of arm 2 is provided a plurality of upstanding or vertical arms designated 6. Surrounding each arm is a plurality of pivotal leaves 7 which are also adapted to surround a loop or ring 8. The mail-bag or bags to be caught designated 9, are strapped or otherwise fastened to the

ring 8. This ring 8 securely holds the bags, but in such manner that the holding means may be released by means or parts later to be described. The pairs of leaves 7 are 5 locked together in position supporting the ring 8 by means of the pins 10 passing through alining eyes of eye members 11 of the leaves. Each pin 10 has pivotally or 10 flexibly connected thereto a link member 12 which in turn is loosely or pivotally connected to an arm 13 pivotally fastened at 14 to the adjacent arm 6. A second link 15 is 15 pivotally or loosely connected to arm 13 which is preferably of flexible material and passes through an eye member 16 carried by 20 a bracket or arm 17. The arms 17 have pivotally fastened thereto as at 18, trip arms or members 19 adapted to overlap or extend beyond the inner end of each other as shown in 25 Figs. 6 and 7. To the outer ends of the trip members 19, the flexible members 15 are fastened.

Now describing the means for catching the mail-bag, the same is supported by a stationary member such as a pillar or support 20 which is mounted along a siding of a railway track. To the pillar 20 is rigidly fastened a stationary head which preferably 25 has a reduced body or post 21 rising from a base 22 from which may depend a screw threaded shank 23 adapted to engage screw threads provided in a hollow portion of pillar 20 and thus serve as one form of means whereby the head may be rigidly fastened 30 to the pillar.

Numeral 24 designates a catching arm which is mounted to turn or swing about the head 21 and is specifically connected in operative relation thereto by means of a turnable hollow head, drum or housing 25 and parts carried thereby, one form of the means for rigidly connecting the arm and hollow head together being shown at 26, where inter-engaging screw threads between the parts 35 are provided.

Subsequent to the catching of a mail-bag, the arm 24 and housing or head 25, is positively revolved through the medium of a coiled band spring 27 which is fastened to the body or post 21 as by means of set screws 28 and to the turnable housing by set screws at 29. This spring 27 is supported by an annular plate or the like 35 which is rigidly fastened to the post 21 as by means 40 of brackets 35'. It is obvious that this outer end of the spring may be fastened to the housing in any suitable manner. As shown, the end projects interiorly of the housing as through an opening or slot 30, and the slot and projecting end is covered by a shield or plate 31 fastened to the housing by means of screws 32. The arm 24 is 45 positively maintained in projected position by means of a latch bolt 33 engaging a socket or slot 34 provided in the post 21. Fas-

tened rigidly to the turnable housing 25, interiorly thereof, as by means of set screws 26, is a plurality of annular or ring shaped bearing members 36, one of which is located adjacent the top of the housing and 50 the other adjacent the bottom thereof. Said post 21 may extend loosely through the bearing members 36 as shown. The lower bearing member 36 is located adjacent the base 22, which base serves as a bearing member, 55 and between these adjacent bearing members may be mounted in a suitable manner, anti-friction means shown as balls 37. Adjacent the top of post 21 is rigidly fastened as by 60 means of brackets 38, an annular plate 39 upon which loosely rests a bearing member in the form of a ring designated 40. Through this bearing member 40 the post 21 may loosely extend. Intermediate plate 39 and bearing members 36 and 40, may be 65 provided suitable anti-friction means shown as balls at 41 and 42 respectively.

Suitable means is employed for checking the movement of the turnable arm and housing thereof, and in such manner as not to 70 impart severe shocks or jolts to the parts. Such means may be as follows: Adjacent the top and bottom of the post 21 are provided grooves 43 which are preferably semi-circular, and the vertical wall of which starts 75 from the peripheral wall of the post 21 and extends gradually inwardly and terminates at the peripheral wall of said post. In this manner a wall that is not strictly annular, but one that may be termed a cam wall, is 80 provided. Into the grooves 43 are adapted to extend brake blocks or members 44, the inner ends of which directly bear against the cam walls. These brake blocks may be supported in any suitable manner and as shown, 85 slide in sleeves 45 which have screw threaded engagement at 46 with the housing. Into the sleeves 45 are screwed, set screws or plugs 47, and intermediate these plugs and the blocks are positioned coil springs 48 which 90 project and maintain the brake blocks inwardly and in frictional engagement with the cam walls. It will be realized that through the extent of adjustment of the set 95 screws 47 into the sleeve, that the tension 100 of the spring 48 may be regulated.

Interiorly of the arm 24 is fastened as by means of ribs 49, a cylinder or hollow casing 50. In this casing 50 is slidably mounted the latch bolt 33. A guide plate 51 is secured 105 interiorly of the casing 50 and therethrough slidably passes a flexible latch shifting member 52. This latch shifting member is positively fastened at 53 to the latch bolt 33 and surrounding the shifting member intermediate 110 said bolt and plate 51, is mounted a coil spring 54 which normally projects the bolt beyond the casing and in position to engage the socket 34.

Supported from the arm 24 in any suitable 115

manner, is a bracket 55 which terminates in a hook 56, one arm of which is designated 57. To the bracket 55 as at 58, is pivoted a lock arm or member 59 adapted to normally maintain the hook closed. On arm 57 is provided an abutment or stop member 60 against which said pivoted lock member bears. One end of the flexible latch shifting member 52 is fastened to an arm of the lock member 59 as at 61; said flexible member 60 preferably passing over a guide member in the form of a pulley 62 located adjacent the outer end of arm 24. It will be noted and observed by reference to Fig. 7 that the lock member 59 is mounted so that in its travel, it will strike both of the trip members 19, specifically the overlapping portions thereof. In use, arm or bracket 2 is projected from a car having fastened thereto a ring such as 8 or its equivalent, and the mail-bag or bags suspended thereon. The catching apparatus is also adjusted so that arm 24 will be projected at right angles to the direction of the track. As the car travels past the arm 24, the arm 57 of hook 56 enters the ring 8 and lock member 59 strikes the trips 19, shifting the same and accordingly the flexible links 15, arms 13, links 12 and pins 10. The pins 10 through this action are moved out of the eyes of eye members 11, whereupon the hook engages the ring and positively slides the same out of engagement with the leaves 7, carrying the same thereon. As the hook passes through the ring, the impact of the ring thereagainst tilts the lock member 59 which accordingly shifts by pulling outwardly the flexible latch shifting member 52, which in turn slides the latch bolt 33 therewith and out of engagement with its keeper socket 34. The impact of the ring 8 against said lock member, carries the ring past the lock member in which position it is locked, as the lock member cannot move outwardly due to its abutment against the stop or abutment member 60. As the latch bolt disengages its keeper socket, spring 27 thereupon shifts the turnable housing 25 and accordingly the arm 24. During the turning movement, the housing through the medium of the bearing members 36, turns on the base member 22 and bearing member 40, friction between said parts being reduced by means of the balls employed, as shown. As the housing turns, its movement is braked or gradually impeded by the frictional and yielding engagement of the brake members 44 against the cam walls of the grooves 43. This braking action being further assisted and friction increased between the wall and the brake members due to the cam formation of the walls. The brake members and grooves are of such construction and so arranged that the arm 24 turns to any extent desired, such as for a quarter of a revolution 65 or a half of a revolution preparatory to an-

other catch. Arm 24 preparatory to another catch is moved to projected position, and as such position is reached the latch bolt 33 will automatically slide into engagement with the keeper socket 34 pressed by the 70 spring 54.

Numerous details in the construction of the device may be varied and hence are reserved providing they fall within the spirit and scope of the appended claims. 75

Having thus described my said invention, what I claim as new and desire to secure by Letters Patent is:—

1. In apparatus of the class described, a post member, an arm turnable relative to 80 said post member, means on said arm to engage an article, means connected to said arm and to said post operating to turn said arm after engagement with an article by said means, and means on said arm frictionally engaging said post for the purpose 85 specified.

2. In apparatus of the class described, a stationary post member, a turnable arm member thereon, means on said arm member to engage an article, one of said members provided with a cam wall, the other of said members provided with a brake member in frictional engagement therewith, means to maintain said arm in projected position and means to return said arm to normal position after release by said means. 90 95

3. In apparatus of the class described, a stationary post member, an arm turnable relatively to said post member, means on 100 said arm to engage an article, said post member provided with a cam wall, said arm provided with a brake member in frictional engagement with said wall, means to yieldably mount said brake member, and means 105 to maintain said arm in projected position, and means to return said arm to normal position upon release by said last means.

4. In apparatus of the class described, a post member, an arm turnable relatively to 110 said post member, means on said arm to engage an article, said post member provided with a groove having a cam wall, said arm having a hollow portion, a brake member extending into said groove having a part in 115 frictional engagement with said wall, said brake member located within the hollow portion, a support member for said brake member, and a spring bearing against said brake member. 120

5. In apparatus of the class described, a post member, an arm turnable relatively to 125 said post member having a hollow portion extending around the same, means on said arm to engage an article, said post member provided with a groove having a cam wall, a brake member extending into said groove having a part in frictional engagement with said wall, said brake member located within the hollow portion, a sleeve for said brake 130

- member extending from said hollow portion, a plug member extending into said sleeve, and a spring mounted intermediate said plug member and said brake member.
- 5 6. In apparatus of the class described, in combination with stationary means, an arm mounted therein, catch means on said arm, means to maintain said arm in projected position, and means intermediate said housing and said stationary means to return said arm to normal position upon release of said last means.
- 10 7. In apparatus of the class described, in combination with a stationary member, a hollow arm turnable relatively thereto, a latch member to fasten said arm to said member and in projected position, means operable to shift said latch extending through said hollow arm, and means to return said arm to normal position after shifting of said latch.
- 15 8. In apparatus of the class described, in combination with a stationary member, an arm turnable relatively to said member having a housing mounted on said member, latch means engageable with said member to maintain said arm in projected position, means to shift said latch mounted on said arm, and brake means intermediate said member and said housing.
- 20 9. In apparatus of the class described, a post, an arm turnable relatively thereto, a housing on said arm, a spring fastened to said post and to said housing, and brake means intermediate said housing and post.
- 25 10. In apparatus of the class described, a stationary member, an arm turnable relatively thereto, a latch member to maintain said arm in adjusted position, an article-engaging member on said arm, a shiftable lock member for said latch through movement of said lock member.
- 30 11. In apparatus of the class described, in combination with stationary means, an arm turnable relatively thereto, means to retard turning movement of said arm in one direction, a spring fastened to said stationary means and to said arm, and latch means on said arm engaging said stationary means.
- 35 12. In apparatus of the class described, in combination with stationary means, an arm turnable relatively thereto, means to fasten said arm in projected position, and means to disengage said fastening means operable through engagement with an article caught and means to retard turning movement of said arm in one direction.
- 40 13. In apparatus of the class described, in combination with stationary means, a turnable hollow arm having a housing engaging said stationary means, a latch to secure said arm in projected position, a pivoted member engageable with an article caught, and means intermediate said pivoted member and said latch member extending through

said hollow arm to shift the latch member through shifting of said pivoted member.

14. In apparatus of the class described, in combination with stationary means, an arm turnable relatively thereto, an article engaging member, a lock member for said member, a latch to secure said arm in projected position relative to said stationary means, a spring pressing against said latch, and means to shift said latch operable through movement of said lock member.

70 15. In apparatus of the class described, in combination with stationary means, an arm turnable relatively thereto, an article engaging member on said arm, a lock member for said member, a latch member to maintain said arm projected relatively to said stationary means, a spring pressing against said latch member, and flexible means connecting said latch member and said lock member.

75 16. In apparatus of the class described, in combination with stationary means, an arm turnable relatively thereto, an article engaging member on said arm, a lock member for said member, a latch member to maintain said arm projected relatively to said stationary means, a casing for said latch member, a spring in said casing pressing against said latch member, and flexible means connecting said latch member to said lock member.

80 17. In apparatus of the class described, in combination with stationary means, an arm turnable relatively thereto, a hook member on said arm, an abutment member on said hook, a pivoted lock member for said hook engageable with said abutment, a slideable latch member to maintain said arm projected relatively to said stationary means, a casing for said slideable lock member, a plate in said casing, a spring mounted intermediate said plate and latch member, a flexible latch shifting member connected to said latch and to said lock member, and guide means for said shifting member.

85 18. In combination with a moving body, support means and an article, a pivoted leaf on said support engaging said article, a lock member securing said leaf in locked position relatively to the article, a trip member, means to actuate said lock member through movement of said trip member, and means on said moving body engageable with said trip member.

90 19. In combination with a moving body, support means and an article, a pivoted leaf on said support means engaging said article, a lock member to secure said leaf in locked position, a pivoted arm, means connecting said lock member to said arm, a pivoted trip member, means to connect said trip member to said arm, and means on said moving body engageable with said trip member.

95 20. In combination with a moving body, support means and an article, a pivoted leaf

engaging said article, a pin to lock said leaf, |
a pivoted arm, a link connecting said arm |
and said pin, a second link connected to said |
arm, a pivoted trip member, said second link |
5 connected to said trip member, and means |
on said moving body to engage said trip |
member.

In testimony whereof I affix my signature
in presence of two witnesses.
